UNITED STATES PATENT OFFICE.

EMIL LINDERME, OF DETROIT, MICHIGAN, ASSIGNOR TO EMIL SCHWARZ, OF DETROIT,
MICHIGAN.

BOTTLE-WASHING BRUSH.

1,274,909.

Specification of Letters Patent. Patented Aug. 6, 1918.

Application filed March 25, 1918. Serial No. 224,655.

To all whom it may concern:

Be it known that I, EMIL LINDERME, a citizen of the United States of America, residing at Detroit, in the county of Wayne 5 and State of Michigan, have invented certain new and useful Improvements in Bottle-Washing Brushes, of which the following is a specification, reference being had therein to the accompanying drawings.

10 This invention relates to a bottle cleaning brush, and more particularly to certain improvements in connection with that type of brush disclosed in my pending application on a bottle cleaning device, filed October 18, 15 1917, Serial No. 197,225. In this particular application there is shown a holder in which a flexible member is mounted and the present invention aims to provide a flexible member with simple and effective means, in a 20 manner as hereinafter set forth for positively anchoring the flexible member in its holder, so that during its use the flexible member will not become accidentally detached.

25 The invention will be hereinafter described and then claimed and reference will now be had to the drawing wherein there is illustrated a preferred embodiment of my invention but it is to be understood that the same is susceptible to such changes 30 as fall within the scope of the appended claims.

In the drawings,

Figure 1 is a side elevation of the brush; 35 Fig. 2 is a horizontal sectional view taken on the line II—II of Fig. 1;

Fig. 3 is a similar view taken on the line III—III of Fig. 1, and

Fig. 4 is a perspective view of the holder. 40 The brush is adapted to be used in a machine for washing bottles and is adapted to enter the mouth of a bottle and thoroughly clean, in conjunction with water or a washing solution, the entire inner surface of a bottle. In order that the brush may pass 45 in and out of the mouth of a bottle, it is made of a flexible material, such as rubber, in the form of a flat member 1 having straight side edges 2 adapted for cleaning 50 the side walls of a bottle, a convex upper edge 3 adapted for cleaning the breast of a bottle, and a concave lower edge 4 adapted for cleaning the bottom of the bottle. Adjacent the edges 2 and 4 and on both sides of 55 the flexible member are ribs 5, said ribs add-

ing a degree of rigidity to the edges of the flexible member, yet not interfering with said member being rolled or gathered in passing in and out of a bottle neck.

On both sides of the flexible member and 60 longitudinally thereof are beads 6 extending from the upper convex edge 3 of said member to a point approximately centrally thereof, where the beads meet enlargements 7 serving as stops.

Adjacent the beads 6, on both sides of the flexible member, are lugs 8 and 9, the lugs 8 being in opposed relation at the same side of the beads 6 and contiguous to the convex edge 3 of the flexible member. The lugs 9 70 are in opposed relation on the opposite side of the beads 6 contiguous to the enlargements 7 and both set of lugs are made of the same material as the flexible member 1 and integral therewith.

To support the flexible member a cylindrical holder 10 is employed, said holder having a socket 11 so that it may be attached to the hollow spindle of a bottle washing machine and receive water or washing liquid 80 therefrom, the holder having an opening 12 in communication with the socket 11 so that water may discharge into a bottle to coöperate with the brush in cleaning the interior 85 of the bottle.

The cylindrical holder 10 has a longitudinal bore 13 and opposed side slots 14 communicating with said bore, the side slots and the bore being of a depth equivalent to the length of the beads 6 which are adapted 90 to fit in the bore 13 with the wings or bilateral portions of the flexible member projecting out of the slots 14.

The enlargements 7 are adapted to limit the inward movement of the beads 6 in the 95 bore 13.

The exterior walls of the holder 10, at the slots 14 are provided with sets of notches 15 and 16, the former being adjacent the lower end of the holder to receive the lugs 9 and the latter intermediate the ends of the holder to receive the lugs 8. Since the flexible member is made from a flat sheet of rubber or molded in such form it can be readily twisted, distorted or otherwise 100 manipulated, when being placed in engagement with the holder so that the lugs 8 and 9 will engage in the notches 16 and 15 respectively. After the member is anchored 105 in the holder the lugs prevent longitudinal 110

movement of the flexible member relative to the holder, consequently the brush cannot become accidentally displaced when in use.

What I claim is:

- 5 1. A bottle washing brush comprising a holder having a longitudinal bore and side slots with notches adjacent said slots, a flexible member having beads adapted to fit in the bore of said holder with said member projecting from the slots thereof, and lugs on said member engaging in the notches of said holder.
- 10 2. A bottle washing brush comprising a flexible member having straight side edges, a convex upper edge, and a concave lower edge, beads on both sides of said member adjacent the straight and concave edges

thereof, and lugs centrally of said member on both sides thereof adapted to engage in the holder for said brush.

20

3. The combination with a holder, of a flat flexible brush mounted therein, means on both faces of said brush extending into one side of said holder adapted to prevent displacement of said brush, and means on both faces of said brush and adapted to engage in the opposite side of said holder and coöperate with the first mentioned means.

In testimony whereof I affix my signature in the presence of two witnesses.

EMIL LINDERME.
